UNITED STATES PATENT OFFICE.

ERNEST LOUIS GARNIER, OF NEUILLY-SUR-SEINE, FRANCE.

DEVICE FOR INCREASING THE EFFICIENCY OF FIREARMS AND THE LIKE.

1,327,545.

Specification of Letters Patent.

Patented Jan. 6, 1920.

Application filed March 10, 1919. Serial No. 281,720.

To all whom it may concern:

Be it known that I, ERNEST LOUIS GARNIER, a citizen of the Republic of France, residing at 50 Rue de Longchamp, Neuilly-sur-Seine, France, have invented new and useful Improvements in Devices for Increasing the Efficiency of Firearms and the like, of which the following is a specification.

10 The present invention relates to a helical device which is constructed in such a manner as to fit loosely on the extremity of the barrel of a rifle and to be picked up by the bullet, on the passage of this latter, as it leaves the muzzle of the rifle. In this way the helical device is carried away by the bullet and constitutes therefor a sort of temporary feather, such as is fitted to arrows. The purpose of the device is to insure 15 greater efficiency of fire by considerably increasing the number of bullets which find the target and thus reducing the number of wasted bullets.

20 In the accompanying drawing, which represents, purely by way of example and in no way limitatively, a device constructed according to the invention;—

25 Figure 1 shows, in section, the apparatus fitted to the extremity of the barrel of the rifle, the bullet being on the point of leaving the muzzle.

30 Figs. 2, 3 and 4, to a larger scale, are, respectively, a section along the line 2—2, Fig. 4, an end elevation and a plan of the apparatus removed from the rifle.

35 Fig. 5 is a section along line 5—5, in Fig. 2.

40 Figs. 6, 7 and 8 are views showing the effect produced by a bullet fitted with the device on a target, which, without the device, the said bullet would have merely grazed without penetrating it, or would have passed to one side thereof without touching it.

45 The apparatus consists essentially of a helix with two blades or guiding vanes *a* of appropriate pitch. The hub of the helix is formed in such a manner as to fit loosely on the extremity of the barrel *c* (Fig. 1) of a rifle beyond the fore-sight *c*.

50 In the interior of the hub *b*, whose external or outer orifice *d* is of diameter equal to, or slightly greater than, the caliber of the rifle, that is to say, the internal diameter of the barrel *c*, there is arranged, concentrically with the said orifice, a ring *e*, whose

internal diameter is slightly less than the interior diameter of the barrel *c*. This ring, which is split or cut at two diametrically opposite points *f*, *g*, is held in place and centered in the interior of the barrel *b* of 60 the helix by four springs *h*, which bear against the inner wall of this hub and exercise a strong pressure on the outer walls of the two half-rings in such a manner as to hold them firmly one against the other at 65 the points *f* and *g*.

The bullet *i*, which is intended to be used with the device according to the present invention, is provided at a suitable point with a small circular groove *j* for the purpose of 70 receiving and seating the two-piece ring *e*.

The method of operation is the following, supposing the device to have first of all been fitted to the extremity of the barrel *c*.

75 At the moment when, after firing, the bullet *i* is on the point of leaving the barrel *c*, it comes into contact with the ring *e*. As the internal diameter of this ring is smaller than the external diameter of the bullet *i*, the two halves of the said ring separate one 80 from the other against the pressure of the springs *h*, and at the moment when the groove *j* in the bullet *i* arrives opposite the ring *e*, the two halves of this latter enter this groove as they are pressed or forced 85 together under the action of the said springs; this attaches the helix *a* to the bullet *i*, which thus carries away with it the helix picked up in this manner by the bullet in its passage, so that the whole leaves the 90 barrel of the rifle together.

Under these circumstances, it will be easily understood that a bullet, which, if not fitted with the device according to the invention, would merely graze a target *k* or 95 would pass it without touching it at a distance from it less than the radius of the helix and would in consequence be lost, will on the contrary, if fitted with the device herein described, be held up by that one of the blades 100 of the helix *a* which first comes into contact with the target *k* (Fig. 6). The bullet *i* being thus deflected from its trajectory, will begin to penetrate into the target (Fig. 7) causing deformation of the blades or vanes 105 of the helix, which latter bear against the target *k* without penetrating into it, after which the bullet *i*, by virtue of its momentum, leaves the helix *a* by pushing apart the two halves of the ring *e* against the action 110

of the springs h , and penetrates alone into the target (Fig. 8).

It is therefore evident that the device described above and shown in the accompanying drawing, by considerably reducing the number of lost bullets, increases to the same extent the efficiency of the rifle for firing purposes.

It is obvious that the invention is not strictly limited to the arrangements shown in the accompanying drawing and described above, and that constructional details could be modified in so far as circumstances or practical requirements might render such modifications desirable or necessary.

I claim:

1. In a fire-arm, the combination with a bullet having a tapered nose and provided with an annular groove on its exterior transverse to the axis of the bullet, of a metal screw propeller having flexible blades provided with a hollow hub detachably connected to the forward end of the barrel, the forward end of said hub being partly closed and provided with an axial opening of greater diameter than the bore of the fire-arm at the muzzle, a segmental ring housed in said hub between said partly closed end and the muzzle of the fire-arm, and resilient means for attaching said segmental ring to said hub and for causing it to project into engagement with the periphery of the bullet as it leaves the fire-arm.

2. In a fire-arm, the combination with a bullet having a tapered nose and provided with an annular groove on its exterior transverse to the axis of the bullet, of a metal screw propeller having flexible blades provided with a hollow hub detachably connected to the forward end of the barrel, the forward end of said hub being partly closed and provided with an axial opening of greater diameter than the bore of the fire-arm at the muzzle, a segmental ring housed in said hub between said partly closed end and the muzzle of the fire-arm, and a series of springs mounted in said hub and pressing inwardly on said segmental ring normally closing the breaks in said ring and causing it to project inwardly beyond the circumference of the bore of the small arm at its muzzle, but permitting the nose of the bullet to distend said ring segment against the action of said springs, thereby causing said ring segments to snap into engagement with said groove as the bullet leaves the muzzle of the small arm.

circumference of the bore of the small arm at its muzzle, but permitting the nose of the bullet to distend said ring segment against the action of said springs, thereby causing said ring segments to snap into engagement with said groove as the bullet leaves the muzzle of the small arm.

3. In a fire-arm, the combination with a bullet having a tapered nose and provided with an annular groove on its exterior transverse to the axis of the bullet, of an auxiliary projectile, carried by the small arm at its muzzle, and provided with a hollow hub detachably connected to the forward end of the barrel, the forward end of said hub being partly closed and provided with an axial opening of greater diameter than the bore of the fire-arm at the muzzle, a segmental ring housed in said hub between said partly closed end and the muzzle of the fire-arm, and resilient means for attaching said segmental ring to said hub and for causing it to project into engagement with the periphery of the bullet as it leaves the fire-arm.

4. In a fire-arm, the combination with a bullet having a tapered nose and provided with an annular groove on its exterior transverse to the axis of the bullet, of an auxiliary projectile, carried by the small arm at its muzzle, and provided with a hollow hub detachably connected to the forward end of the barrel, the forward end of said hub being partly closed and provided with an axial opening of greater diameter than the bore of the fire-arm at the muzzle, a segmental ring housed in said hub between said partly closed end and the muzzle of the fire-arm, and a series of springs mounted in said hub and pressing inwardly on said segmental ring normally closing the breaks in said ring and causing it to project inwardly beyond the circumference of the bore of the small arm at its muzzle, but permitting the nose of the bullet to distend said ring segment against the action of said springs, thereby causing said ring segments to snap into engagement with said groove as the bullet leaves the muzzle of the small arm.

ERNEST LOUIS GARNIER.
